UNITED STATES PATENT OFFICE

ALFRED ALSAKER, OF CHICAGO, ILLINOIS, ASSIGNOR TO THE DELTA-STAR ELECTRIC COMPANY, OF CHICAGO, ILLINOIS, A CORPORATION OF ILLINOIS

SWITCH

Application filed April 29, 1929. Serial No. 358,893.

This application is a continuation in part of my copending application Serial No. 237,678, filed December 5, 1927, and this invention relates to electric switches, more particularly to the outdoor gang operated type such as are commonly employed for power disconnect purposes. While the invention is particularly applicable to this service, it is not intended to limit it to that use.

Switches of the present type are infrequently operated and after remaining closed for long periods of time during which they are subjected to all sorts of weather conditions, there is a tendency for the switch contacts to stick together. Ice or sleet may form on the contacts if the contacts are exposed, thus rendering opening of the switch rather difficult. Unless special means is employed for separating the contacts, the insulator stacks supporting the contacts may be subjected to excessively high mechanical stresses. It is a particular object of the present invention to provide a simple switch mechanism wherein the preliminary ice breaking movement of the switch contacts is obtained without inducing excessive mechanical stresses in the insulators.

The present form of switch comprises two supporting insulators upon one of which a relatively long switch blade is mounted and upon the other of which a relatively short switch contact is mounted. Both insulators are rotatable and are mechanically interconnected so that rotation of one of the insulators produces rotation of the other. The blade engages the contact with a wiping movement thus forming a clean contacting surface between the blade and its contact. Upon opening the switch the blade and contact separate with a shearing motion, and because of the relatively long length of the blade and the relatively short turning radius of the rotatable contact member, a great shearing force is generated which is sufficient to break the bind between the blade and the contact member whether this binding is caused by corrosion, or by ice or sleet. This great shearing force is, of course, due to the fact that the blade and the contact

both rotate from one another. No excessive mechanical stresses are induced in the supporting insulator stacks.

A shelter in the form of a sleet shield is mounted upon one of the contacts and moves therewith, thus preventing the formation of ice or sleet upon that contact and likewise when the switch is closed the sleet shield minimizes or prevents the formation of ice between the switch blade and the contact.

The sleet shield is, in the present embodiment of the invention, in the form of a plate overhanging the switch contact and secured thereto. By this arrangement the inertia of the moving mass is considerably reduced.

The attainment of the above and further objects of the invention will be apparent from the following specification taken in conjunction with the accompanying drawings forming a part thereof.

In the drawings:

Fig. 1 is a side elevational view of the switch forming the present invention;

Fig. 2 is a bottom plan view of the switch operating mechanism;

Fig. 3 is an enlarged view showing the switch contact and manner of securing it to insulators;

Fig. 4 is a bottom plan view of Fig. 3; 80

Fig. 5 is a fragmentary section taken along the line 5—5 of Fig. 3.

The switch shown in Fig. 1 is of the underslung type and comprises two insulator stacks, 1 and 2, support from a base 3 which may be in the form of a channel as is the usual construction. The insulator stacks 1 and 2 are connected to the channel base 3 through rotary bearings 4 and 5 which are interposed between the channel 3 and the insulator caps 6 and 7.

The rotary bearings may be of the type disclosed in my copending application, Serial No. 137,926, filed September 27, 1926. The insulator stack 1 is fitted at its lower end with an adapter 10 suitably secured to the insulator pin 11 by means of bolts 12. A contact 13 in the form of a substantially flat rectangular plate is bolted to the adapter 10 by means of four bolts indicated at 14. 100

The bolts 14 also serve to secure a T shape reenforcing member 15 to the blade 13. A bearing stud 18 having two forks at 19 is secured to the reenforcement member 15 by 5 bolts 20 and acts as a bearing member for a lug support 22 having a projecting lug 23 to which a lead in line for the switch may be attached. The lug support is held in the bearing stud and is free to rotate with 10 respect to the lug support. As a result of this arrangement the lug support 22 is held stationary by the line that is connected to the arm 23 while the bearing stud rotates with the insulator stack 1. A flexible conductor in the form of a copper braided wire 24 connects the lug support 22 with the contact 13 so that all of the current flowing through this switch is carried by 15 the conductor 24 and does not have to pass through the bearing member.

A bracket 28 is bolted to the contact 13 by means of two bolts 29 and supports a sleet shield 30 which is riveted or otherwise 25 suitably secured to the bracket. The sleet shield 30 overlies the end of the contact 13 that is engaged by the switch blade in a manner to be more fully set forth presently and prevents the accumulation of ice or sleet upon the contact.

30 A switch blade 35 is secured to the bottom of the insulator stack 2 in substantially the same manner as is the contact 13, an adapter 36 similar to the adapter 10 being 35 interposed between the switch blade 35 and the insulator pin 11. The blade 35 has a T shaped reenforcing member 38 secured to the bottom thereof and this reenforcing member serves as a support for a bearing stud 40 of a construction identical with the construction of the bearing stud 19. The bearing stud 40 supports the lug support 41 identical to the lug support 22 upon the insulator 1. A flexible braided copper conductor 42 connects the lug support with the switch blade 35. A pair of contact jaws 45 are mounted upon springs 46 at the end of the switch blade 35, said contact jaws being adapted to receive the contact 13 between them.

50 An operating lever 50 is adapted to rotate the insulator stack 1, said lever being secured to the bearing member 4 as shown in my above referred to application. The 55 rotary motion of the insulator stack 1 is transmitted by means of a crank 51 secured to the insulator cap 6 and a lever 52 which connects lever 51 with a corresponding crank 53 secured to the insulator cap 7 at 60 the top of the insulator 2. When the switch is in the closed position the crank 51 and the lever 52 are in substantial alignment and therefore resist any tendency of the switch to open due to the force between 65 the contact 13 and the switch blade 35 by

reason of current flowing through the switch.

To open the switch the operating lever 50 is rotated in a counter clockwise direction as seen in Fig. 2, thereby rotating the switch 70 blade in a clockwise direction as seen in Fig. 2. It is to be noted that at the commencement of the switch opening movement the switch contact 13 has a greater angular velocity than the switch blade 35. Due to the 75 toggle action of the members shown a relatively great force may be exerted to break the switch blade 35 from the contact 13 through any ice or corrosion that may have formed. When the switch is closed the reverse operation occurs and the contact 13 is moved between the contact jaws 45 on the switch blade 35 with a shearing action. This shearing action tends to clean the 80 switch contacts as the switch is closed thereby maintaining good electrical contacts. It is to be noted that the edge of the switch contact 13 is beveled and that the contact jaws 45 flare outwardly. This facilitates 85 the movement of the contact between the jaws in that it serves as a guide for guiding the contacts into the jaws during the switch closing movement.

90 There is a distinct advantage in arranging the levers 51 and 52 so that they are in substantial alignment when the switch is closed and in providing an operating connection such as the lever 50 for rotating the insulator stack 1, and from this stack transmitting the motion to the stack 2. In 95 switches of this kind the operating lever is generally turned by means of a series of links which extend for an appreciable distance from the switch. The motion is transmitted through these links to the lever 50. 100 Assume that the switch as initially installed is adjusted so that when the operating handle or the like at the end of the actuating link work is actuated to its extreme position the motion is transmitted to the crank 105 50 to rotate the insulator stacks 1 and 2 into the closed position as shown in the drawings. After a period of time it may happen that a certain amount of free play is developed 110 in the operating connection extending up to the lever 50 whereby the same amount of operation will produce slightly less turning of the insulator 1, say five degrees less. This means that under such condition when the switch is actuated to its closed position the 115 contact 13 that is mounted upon the insulator stack 1 will be five degrees out of its true closed position. The same applies to the crank 51 that transmits the motion through the lever 52 to the insulator stack 120 2, and, when the operating mechanism has been moved to its full closed position the lever 51 will be approximately five degrees out of the position shown in Figure 2 in the 125 example assumed. Under those conditions 130

the lever 53 will be less than one degree out of the position shown in Figure 2, hence the switch blade will be less than one degree out of its true position. Calculations show 5 that this amount is actually less than one-half of one degree. The switch contacts 13 and 45 will therefore engage one another with the result that the circuit through the switch is closed. On the other hand, as 10 assume that the driving connection of the lever were made to the insulator 2 instead of to the insulator 1. Under such condition if the same amount of free play should develop in the link work that transmits motion 15 to the lever 50 then the switch blade would reach its closed position which would be five degrees out of its true position. Due to the great length of the switch blade such a great difference in the angular position of the 20 switch blade may cause it to fall short of engaging the switch contact 13. The same result does not follow from a short angular displacement of the contact 13 due to the fact that this contact is of a much smaller 25 er length.

There is an additional advantage in locating the lever 50 so that the motion is first transmitted to the contact supporting insulator and from it to the blade supporting insulator. This is due to the following condition:

Suppose that the switch has remained closed for a long period of time and the contacts have become corroded together, rendering the opening operation difficult. A 35 certain amount of free play or looseness is inherently present in the connection between the insulators and upon the application of a turning force to the crank 50 to open the switch the force is transmitted to the contact 13 which commences to turn to break the bind between it and the contact 55. This turning commences very slightly in advance of the rotation of the switch blade 40 due to the inherent presence of even trifling amounts of free play. Thus the force which tends to free the contacts from one another is transmitted at a relatively short radius whereby the stresses induced in the insulators is small. Now, by reason of the fact 45 that the crank 51 and the connecting rod 52 are in substantial alignment when the switch is closed a small angular movement of the insulator 1 toward the open position 50 produces substantially no movement of the insulator 2, hence all of the effort necessary to break the bind between the contact plate 13 and the contact 35 may be transmitted through the insulator 1 at the relatively 55 short radius rather than through the insulator 2 and the relatively long blade. This would not be true if the crank 51 and the connecting rod 52 were not substantially in alignment when the switch is closed, even if 60 the actuating force were applied to the crank 65

50 connected to the insulator 1 as shown. On the other hand if the operating lever 50 were directly connected to the insulator 2 and from this insulator the connection extended to the insulator 1 then the initial 70 turning movement would necessarily have to be transmitted to the blade 35 and, since this blade is relatively long, there would be appreciable stresses induced in the insulator stack 2 even if the crank 53 and the rod 52 were in alignment when the switch is closed. 75

In compliance with the requirements of the patent statutes I have herein shown and described a preferred embodiment of my invention. It is however, to be understood that the invention is not limited to the precise construction shown, the same being merely illustrative. What I consider new and desire to secure by Letters Patent is:

1. An electric switch comprising a relatively short contact and a relatively long switch blade both movable into and out of engagement with one another, separate rotatable insulators for the blade and the contact, means for rotating the contact actuating insulator to rotate the contact, and means comprising a crank mechanism between the insulators for transmitting motion to the blade actuating insulator, said crank mechanism being approximately at 85 its dead center position when the switch is closed.

2. An electric switch including a pair of spaced rotatable insulators, a relatively short contact rotated by one of the insulators, a relatively long switch blade rotated by the other insulator, said blade and contact being rotated by their respective insulators into and out of engagement with one another, means for rotating the contact actuating insulator, and means including a crank for rotating the blade actuating insulator, said crank being approximately at its dead center position when the switch is closed. 100

3. An electric switch including a pair of spaced rotatable insulators, a relatively short contact rotated by one of the insulators, a relatively long switch blade rotated by the other insulator, said blade and contact being rotated by their respective insulators into and out of engagement with one another, means for rotating the contact actuating insulator, and means including a crank connecting the contact actuating insulator with the blade actuating insulator for rotating the blade actuating insulator, said crank being approximately at its dead center position when the switch is closed. 115

4. An electric switch including a relatively short contact and a relatively long switch blade both movable into and out of engagement with one another, and means for imparting a relatively great initial angular motion to the contact and a negligible an-

gular motion to the blade to initially break the bind between the blade and the contact.

5. An electric switch including a pair of rotatable insulators, cooperating contact making members actuated by the insulators, means for rotating one of the insulators, and means including a crank connecting the two insulators for transmitting motion from said one insulator to the other insulator, said crank being approximately at its dead center position when the switch is closed.

10. The method of separating a switch blade from its contact which comprises, first retaining the blade substantially stationary and turning the contact about a short radius to break the bind between the contact and the blade, and then actuating the blade away from the contact to its full open position.

15. A switch comprising a rotatably mounted switch blade, a rotatable contact adapted to be engaged thereby, and means for forcing the contact into and out of engagement with said blade, said means including means for simultaneously imparting a relatively great motion to the portion of the contact that engages the blade and a negligible motion to the contacting portion of the blade upon the initial switch opening movement.

20. A switch including a movable switch blade, a contact at the end thereof, a second contact adapted to be engaged by the first contact and forced into firm engagement therewith, means for actuating the second contact to loosen the engagement between the two while the switch blade is maintained substantially stationary, and means for thereafter swinging said switch blade away from said second contact.

25. An electric switch including a pair of crank arms, a connecting rod connecting the two, one of the cranks constituting the driving crank and the other constituting the driven crank, said driving crank having a normal switch open position and a normal switch closed position, said driving crank and connecting rod being in substantially their dead center position when the driving 30 crank is in its normal switch closed position, insulators connected to and actuated with the respective crank arms, and cooperating contact making members actuated by the respective insulators into and out of engagement with one another.

35. An electric switch including a pair of crank arms, a connecting rod connecting the two, one of the cranks constituting the driving crank and the other constituting the driven crank, said driving crank having a normal switch open position and a normal switch closed position, said driving crank and connecting rod being in substantially their dead center position when the driving 40 crank is in its normal switch closed position,

45. insulators connected to and movable with said crank arms, a relatively short contact mounted on the insulator connected with the driving crank arm, and a cooperating relatively long switch blade actuated by the other insulator.

50. 11. A switch of the type wherein a relatively short contact is engaged by a relatively long blade and the switch is opened by rotating the contact about a comparatively short radius and the blade about a comparatively long radius, characterized by the fact that the linear velocity of the end of contact is maintained appreciably above the linear velocity of the contacting end of the blade during the initial switch opening operation.

55. In witness whereof, I hereunto subscribe my name this 23rd day of April 1929.

ALFRED ALSAKER.
